(57) **CLAIM**

The ornamental design for a display screen with graphical user interface, as shown and described.

DESCRIPTION

The FIGURE is a front view of a display screen with graphical user interface, showing the new design.

The broken lines in the drawing illustrates portions of the graphical user interface that form no part of the claimed design.

1 Claim, 1 Drawing Sheet

Top, Matches

Match% is the ratio of matching specifications with respect to the reference state. Match Count is the actual number of specifications that match with the reference state.
